HEAT-RESPONSIVE ELEMENT

Walter H. Freygang, Essex Fells, N. J., assignor to
Specialties Development Corporation, Bloom-
field, N. J., a corporation of New Jersey

Application May 22, 1940, Serial No. 336,497

6 Claims. (Cl. 169—42)

This invention relates to automatic fire detecting apparatus, and more particularly to the heat-responsive elements used in such apparatus.

It is an object of the present invention to provide a heat-responsive element for fire detecting purposes, preferably in the form of a strip or strand of a material which has reaction characteristics with respect to heat, the more common solvents, outdoor exposure, and to mechanical loads which make it superior to other materials used for this purpose.

In devices of this character, heat-responsive elements of a variety of materials, usually in the form of threads or filaments have been used, and it was found that each one of these materials had some property that made it undesirable for the purpose stated.

The apparatus in question is intended for use on a diversity of hazards including airplane engines, and should therefore be capable of withstanding various operating conditions, such as exposure to continuous high temperatures, meteorological and mechanical influences, coupled with the standard requirements of ruggedness and speedy and accurately predictable operation for a given temperature.

In connection with materials employed heretofore, including horsehair, cotton and silk threads, Celluloid, bimetal, and fusible metal, it was found, that one or more drawbacks were present which rendered them undesirable. Such drawbacks were the inclination to rot and other unfavorable aging characteristics, slow response to ambient heat, non-uniformity of mechanical strength and structure, lack of reliability due to the impossibility of maintaining consistent operating characteristics because of a number of uncontrollable factors, as well as the fact that the elements formed of these materials were easily subject to injury and structural weakening on contact with water, oil, gasoline and other common solvents.

My invention aims to overcome the drawbacks found in the heretofore known heat-responsive elements by providing an element for the indication of the presence of fire or temperatures equivalent thereto, which is made of a synthetic material to be described, and preferably, is in the form of thin strips or filaments.

I have found by experiment, including many comparative tests that this synthetic material drawn into a strip or filament forms a fire-sensitive element of a uniform thickness and quality, being factory produced; that it is practically immune to most solvents; that it will not de-

teriorate over long periods when exposed to influences of weather; that it stands up well under prolonged exposure to high temperatures; and finally that it will fail, very quickly and with reasonable certainty at between 400 and 450° F. Further, it is easily workable, and therefore is readily applicable to factory production methods.

In consequence of the stable characteristics of these synthetic strands, elements composed of this material have proven, under numerous tests and actual operating conditions, to be much better suited for the purpose and the conditions set forth above than any other material so far employed therefor.

15 The material in question, is that popularly known by the trade name "nylon". The actual details of the chemical processes involved in the preparation thereof will not be gone into as they do not form a part of this invention. It is a commercially available article, the chemical and other characteristics of which have been described in Letters Patent of the United States, 2,071,250; 2,071,251; 2,071,253 and 2,157,116. The material, in accordance with these Patents 20 is chemically known as a synthetic condensation polymer and may be a synthetic polyamide. This material is obtainable in a number of shapes and forms, but for fire-detecting purposes is preferably employed as a strand or filament of the 25 approximate thickness of a bristle, the exact size being determined by the mechanical requirements of the case.

In order to be better able to illustrate the general range of application of an element of that 30 nature, two examples of fire safe-guarding apparatus have been described incorporating fire sensitive elements of my invention. For a better understanding, reference is now made to the accompanying drawing, wherein:

35 Figure 1 represents, in diagrammatic form, the application of the heat-responsive element to the coverage of an extensive locality, while

Figure 2, in a similar manner, indicates a fire-detecting device which may be applied locally.

40 Figure 3 shows an electric alarm circuit employing the device of Figure 2.

45 There are a great many possible cases where it may be desired to detect a fire or dangerous temperatures, and each of these may call for a different solution. Of the two cases illustrated in the drawing, the apparatus of Figure 1 comprises a heat-responsive strand-like element which is composed of a material in accordance with the present invention and may be of any desired length and fastened about the space to

be supervised, **S** being a supporting wall. The filament is run over pulleys **2**, and supports a weight **3** which, when released, through the medium of a connecting link **4** running over pulley **5**, is able to actuate a lever **6** pivoted about a fixed point **6**. This lever **7** may perform any one of a number of functions such as closing an electric alarm circuit, act as a mechanical intermediary for the release of a larger or remotely operating force for the liberation of a fire extinguishing medium, the closing of doors and other fire safe-guarding operations.

The device illustrated in Figure 2, shows a frame **21**, mounted on a housing structure **22** which contains electrical contact elements **23** and **24** adapted to be electrically connected by a ring-like conductor **25** held away from the contact elements by a filament **26**. The filament **26**, which in function and composition is analogous to the element **1** of Figure 1 is held anchored in the dished portion **27** of frame **21** and at **28**, in the recessed portion of an insulating member **29** which forms a single structure with contact ring **25**. Element **26** is held under tension by means of an expansion spring **210** bearing upon the outer side of frame **21** and on the inner side of member **29**.

It is apparent that upon the rupture of the filament **26**, contact ring **25** through the force of the spring **210** will seat on and electrically bridge the contact elements **23** and **24**. These contact elements may be made part of any desired circuit by proper connection at **211** and **212**. The filament may vary in length from about one to two inches according to need, the device itself being placed at various points along a circuit covering one or more localities. This is shown in Figure 3, illustrative of a representative fire alarm apparatus, wherein **31** is a source of electric current, **32** a conductor leading to an alarm bell **33**, and **34** a plurality of return conductors in each of which is placed a circuit closer **35**, in accordance with Figure 2.

The operation of the heat-sensitive element in the two applications shown, is self apparent. Temperatures of very nearly between 400 and 450° F. will cause an immediate failure of the heat-responsive element, in both instances, with the result that such fire safeguarding measures as have been contemplated are initiated immediately upon the attainment of such temperatures.

It is to be understood that the invention, however, does not reside in any particular application of the heat-sensitive element, but rather in

fire-safeguarding apparatus having as its flame detecting means an element composed of a synthetic polymer of the class described, as will be apparent from the appended claims.

I claim:

1. In a fire safeguarding system for a hazard involving greatly varying temperatures, vibration and varying climatic conditions, the combination of fire safeguarding means, and means for restraining the operation of said fire safeguarding means including an element of a synthetic polymer of the class described having such length and thickness as to produce rapid rupture at its disintegrating temperature.

15 2. In a fire safeguarding system for a hazard involving greatly varying temperatures, vibration and varying climatic conditions, the combination of fire safeguarding means, and means for restraining the operation of said fire safeguarding means including a filament of a synthetic polymer of the class described.

20 3. A fire safeguarding apparatus for hazards of the type described, comprising fire safeguarding operating means, and means restraining said last named means including a flame detecting element of a synthetic polymer of the class described having such length and thickness as to rupture with the desired rapidity at its disintegrating temperature.

25 4. The combination of fire safeguarding means, operating means for said fire safeguarding means, and means normally restraining said operating means including an element of a synthetic polymer of the class described having such length and thickness as to rupture with the desired rapidity at its disintegrating temperature.

5. In a fire safeguarding apparatus for hazards of the type described, the combination of fire safeguarding operating means including a weight, and means restraining said weight from operating including a flame detecting element of a synthetic polymer of the class described having such length and thickness as to rupture with the desired rapidity at its disintegrating temperature.

45 6. In a fire safeguarding apparatus for hazards of the type described, the combination of fire safeguarding operating means including a spring, and means restraining said spring from operating including a flame detecting element of a synthetic polymer of the class described having such length and thickness as to rupture with the desired rapidity at its disintegrating temperature.

WALTER H. FREYGANG.
